Original application March 7, 1944, Serial No.
525,417. Divided and this application March
17, 1948, Serial No. 15,290.

2 Claims. (Cl. 64—30)

1

The invention hereof relates to starters for internal combustion engines and particularly to starter torque limiting means.

This application is a division of copending application, Serial No. 525,417, filed March 7, 1944, for a Starter, now Patent No. 2,446,297.

In a starter of the type indicated, it is usual to employ torque limiting means between an electric motor or driving member and a starter clutch member or jaw which engages a complementary engine clutch means or jaw to start the engine.

While a certain range in the torque transmitting properties of the torque limiting device is permissible, conditions of overload are often created and it becomes necessary to accommodate such conditions in the torque limiting mechanism.

An object of the present invention is to provide a novel and improved torque limiting means of the type indicated.

Another object is to provide torque limiting means which employs the principle of a screw or cam having rotative movement about the screw axis for separating torque members along the axis against a force biasing the members together.

Another object is to provide means of the above-indicated character which is simple and durable in construction, economical to manufacture, and effective in its operation.

The above and other objects and features of the invention will appear more fully hereinafter from a consideration of the following description taken in connection with the accompanying drawing wherein one embodiment of the invention is illustrated by way of example.

In the drawing:

Figure 1 is a side view generally in section, but having parts in elevation, of a starter embodying the torque limiting means of the invention; and

Figure 2 is an exploded perspective of parts of the torque limiting means shown in Figure 1.

Referring to Figure 1, a starter for which the improvement of the invention is adapted, comprises a housing including portions 10 and 11 having clamped therebetween a flange 12 of a bearing partition 13. The housing portion 10 is provided with a radially outer flange 14 formed with bolt openings 15, whereby it is adapted to be bolted to the crank case of an engine.

Mounted on the left end of the housing portion 10, as shown, and extending over the flange 14, is an end closure or baffle 16 having a central opening defined by a portion 17 of substantially cup-shape. An oil seal 18, carried by the portion 17, surrounds and engages a drive sleeve or spline nut 19 which extends into the housing portion 10.

The inner end of the nut 19 carries a packing assembly 20, including a radially outer flange

21 axially engaged by the end of the sleeve 19. The assembly 20 also includes an inner seal 22 which surrounds and engages an enlargement 23 of a meshing or thrust rod 24. The latter has a forwardly extending part 25 of reduced diameter forming a shoulder 26 on the enlargement 23.

The inner surface of the spline nut 19 is provided with long-lead screw threads 27. A screw shaft 28, which has threads 29 complementary to the threads 27, is disposed within the nut 19 and has a bore 30 receiving the extension 25 of the rod 24. At the left end of the screw shaft 28, the bore 30 is enlarged to provide a spring receiving recess 31, which receives one end of an expansion spring 32 disposed about the thrust rod extension 25. The other end of the spring 32 engages a clutch member or jaw element 33 having a cylindrical extension 34 extending into the nut 19. The extension 34 has an axially slidably spline connection 35 to the screw shaft 28. The mesh rod extension 25 extends through an opening in a center web of the jaw member 33 to an outer end of the rod carrying a nut 36.

As the rod 24 is moved to the left, as shown in Figure 1, the shoulder 26 engages, and causes a corresponding movement of, the screw shaft 28. Thus, the jaw 33 is moved into operative engagement with a complementary jaw 37 which, in this instance, is carried by the engine crank-shaft. The spring 32 provides for ratcheting of the jaw 37 on the jaw 33 when the engine starts and before the withdrawal of the jaw 33.

A torque-limiting friction disc pack 39 is disposed within an annular space radially between the spline nut 19 and a sleeve 40, with interspersed ring-like discs axially movably splined to the nut and the sleeve, respectively, as on splines 38 on the outer cylindrical surface of the nut 19. The sleeve 40 has an inwardly turned end flange 41.

A spacer ring 42, Figure 1, is interposed between the end flange 41 and the disc pack 39. Likewise, a spacer ring 43 is interposed between the other end of the disc pack and the end wall 44 of a barrel 45 in the casing section 10.

Referring to Figure 2, the inner surface of the barrel 45 carries helical splines or long-lead screw threads 46 which fit between complementary splines or threads 47 on the exterior of the clutch sleeve 40.

The barrel 45 is mounted for rotation by a bearing 48 and a bearing ring 49 at opposite ends of the barrel. A ring nut 50 is threaded into the outer end of the barrel 45 to the left of a spring positioning ring 51. As indicated by dotted lines in Figure 2, the inner face of the ring 51 is provided with a plurality of recesses 52, the sides of which are defined by arcs. Pins 53 project from the centers of the recesses 52. Received in each of the recesses 52, and positioned thereby, is an

outer expansion coil spring 54. An inner expansion coil spring 55 is disposed within each outer spring 54, and has one end fitting over one of the pins 53. The other end of the inner spring 55 fits within one of recesses 56 formed in the end flange 41 of the sleeve 40. The corresponding end of the outer spring 54 engages the flange 41.

Springs 54 and 55 may be employed to exert a given thrust on the clutch sleeve 40, and which thrust is transmitted throughout the spacer ring 42 to the disc pack 39. However, the barrel 45, which is driven by planetary gearing, later set forth may, by reason of variations in the load encountered, vary the effective force on the disc pack 39 because of the interfitting helical splines 46 and 47. When the torque increases, the helical splines 46 and 47 are rendered effective to relieve the pressure provided by the assembly of springs 54 and 55. Thus, the friction disc torque limiting device may be set to have its torque transmitting properties maintained within a certain predetermined range.

Extending inwardly from the end wall 44 of the barrel 45 are a plurality of stub shafts 57. Rotatably carried by each of the stub shafts 57 is a planet gear 58. The inner surface of the housing portion 10 adjacent to its right-hand end is provided with an internal orbit gear 59.

The planet gears 58 mesh with the orbit gear 59 and also with a sun gear 60 rotatably mounted on hollow stub shaft 61 which extends to the right from the end wall 44. The shaft 61 is provided with an inwardly extending shoulder 62. The outer, or left-hand, end of the stub shaft 61 receives the enlargement 23 of the shaft 24.

Operatively connected to the sun gear 60, as by being integral therewith, is a planetary gear carrier 63 having a plurality of stub shafts 64 projecting therefrom. Rotatably carried on each of the stub shafts 64 is a planet pinion 65 which meshes with the orbit gear 59, and another sun gear 66. The latter rotates on the sleeve-like shaft 61 and also carries a planet gear carrier 67 provided with stub shafts 68, each of which carries a rotatable planet gear 69.

The planet gears 69 mesh with an internal orbit gear 70 carried by the bearing partition 13. The planets 69 also mesh with a pinion 71 on one end of an armature shaft 72.

The bearing partition 13 has an inwardly extending web 8 which carries a bearing assembly 9 supporting the left-hand end of the armature shaft 72.

Drivably carried by the armature shaft 72 is a flywheel 73, which with the shaft, a commutator 74, and pinion 71, and appurtenant parts constitutes a rotatable unit.

The field windings 75 of the motor are electrically connected to terminals in an outlet 76 on the housing portion 11.

The rod 24 has a reduced portion at the shoulder 62 and extends past this shoulder through the sleeve 61 into the bore 77 of the armature shaft 72. Within the bore 77, the rod is connected to another thrust rod 78 which extends beyond the right end of the armature shaft, and is slidably in a sleeve 79 carrying a bevel gear 80.

A connection 81, between the thrust rods 24 and 78, provides an abutment for one end of an expansion spring 82. This spring 82 surrounds the rod 24 and bears at its other end, against the shoulder 62. The tendency of the spring 82 is to retract the thrust rod 24 and clutch jaw member 33.

In operation, after the starter jaw 33 has been actuated to engagement with the engine jaw 37, and the driving members to the left of the pinion 71 are under the driving force of the latter, since the barrel 45 is axially stationary, if the frictional characteristic or torque slip value of the pack 39 has increased over the value to which it was adjusted by the springs 54 and 55, and a greater torque is encountered, the splines 46 will act on the splines 47 with a screw-like action urging the sleeve 40 axially to the left, as shown, against the forces of the springs 54 and 55. This action momentarily separates the inner and outer discs of the pack 39 from each other.

If the aforementioned adjusted frictional characteristic or torque slip value of the pack 39 does not increase, the mentioned screw action will not occur to axially separate the discs of the pack 39, but the discs of the latter will frictionally slip relative to each other when the adjusted valve is exceeded.

Although only one embodiment of the invention has been illustrated and described, various changes in the form and relative arrangements of the parts may be made to suit requirements.

What is claimed is:

1. In an engine starter, a clutch member adapted for cooperation with engine clutch means to start the engine, a rotatable barrel driving member, a sleeve concentric of said barrel and helically spline connected thereto, a friction disc pack within said sleeve and yieldably connecting said clutch member and sleeve, spring means acting upon said sleeve for biasing the discs of the pack into engagement with each other and opposing relative movement between said barrel and said sleeve while permitting driving rotative movement of said barrel and sleeve together, said spline connection having a pitch angle to cause relative axial movement between the sleeve and barrel in response to a predetermined load on said sleeve to overcome said spring means thereby to disengage the discs of the pack.

2. In an engine starter, a clutch member adapted for cooperation with engine clutch means to start the engine, a rotatable barrel driving member, a sleeve in the barrel having an end flange and including a helical splined connection to the barrel, a friction disc pack within said sleeve and yieldably connecting said sleeve to said clutch member, a ring nut in the barrel, expansion springs between the end flange and the ring nut for urging the discs of said pack into frictional engagement with each other, and said spline connection having a pitch value effective upon a load in excess of a predetermined value being applied to the sleeve for moving said sleeve axially in opposition to said springs to disengage the discs of the pack from each other.
